UNITED STATES PATENT OFFICE.

BENJAMIN F. LOCKWOOD, OF FREWSBURG, NEW YORK.

SYRINGE.

No. 921,130.

Specification of Letters Patent.

Patented May 11, 1909.

Application filed May 2, 1908. Serial No. 430,430.

To all whom it may concern:

Be it known that I, BENJAMIN F. LOCKWOOD, a citizen of the United States, residing at Frewsburg, in the county of Chautauqua and State of New York, have invented a new and useful Improvement in Syringes, of which the following, taken in connection with the accompanying drawing, is a full, clear, and exact description.

The invention relates to injecting syringes and the objects of my invention are first, to provide a receptacle for storing fluids without contact with air, containing an air tight collapsible sack containing air so as to resiliently hold said fluids without danger of breakage of said receptacle due to the expansion and contraction of the contained fluid on account of the varying temperatures to which it may be subjected; second, to provide means for producing fluid pressure upon said collapsible sack whereby the contained fluid in said receptacle may, when desired, be forced from said receptacle without air contact; and third to provide an injecting needle and sealed nozzle whereby said injecting needle may be inserted into said nozzle and the contained fluid in said receptacle without contact with air so that said fluid may be injected through said needle entirely free from air.

In the drawings, Figure 1 is a lengthwise sectional view of a sealed tube, preferably of glass, having a collapsible partition therein dividing said tube into two compartments and a sealed nozzle at one end of said tube. Fig. 2 is a sectional view of a tube and nozzle having a partition, the rear end of the tube being fitted with a resilient pressure bulb preferably of rubber. Fig. 3 is a sectional view of a tube having a nozzle and resilient partition therein, the end opposite said nozzle being fitted with a piston to give pressure upon said resilient partition. Fig. 4 is a sectional view of a syringe tube having a nozzle, showing my improved form of injecting needle inserted in said nozzle, and a piston having a resilient air chamber on its compression surface within said tube. Fig. 5 is a lengthwise sectional view of the nozzle portion of the tube and the injecting needle inserted therein. Fig. 6 is a lengthwise sectional view of a sealed tube having an air-tight, pliable, collapsible, sack for containing air or volatile fluid under pressure, said tube being shown in process of refilling.

Similar numerals refer to corresponding parts in the several views.

The numeral 10 indicates the receptacle, which is preferably made in tubular form of glass and sealed at each of the ends 11 and 12, as shown in Fig. 1. Before end 11 of tube 10 is drawn down in the process of sealing an air tight collapsible sack 14 is inserted within the same, the sack being filled with air under pressure or with a volatile fluid capable of producing fluid. Sack 14 may be entirely free from attachment to the inner side of tube 10, as shown in Fig. 6, but preferably a slight annular enlargement 13 is made in the glass about midway of the length of the tube and an annular attachment is made at 15 of the outer sides of the sack 14 within said enlargement so that when the fluid is injected or forced into the tube 10 the sack 14 will turn invertingly inward upon itself, as shown in Fig. 1 to the degree necessarily required by the amount of fluid. The pressure within sack 14 will form a resilient cushion for the fluid so contained within the tube 10. Sack 14 may be made of sheet rubber or any collapsible air tight material which would serve the purpose.

Sack 14' may be made in the modified form of a half sack open at one end and having an annular attachment 16 which modification is shown in Figs. 2 and 3. It is obvious that such a modified form of sack 14 is necessary where the pressure is obtained from an elastic bulb, as shown in Fig. 2 or a piston, as shown in Fig. 3.

End 12 is drawn out in a tubular nozzle 17 and then in a smaller portion 18 which may be easily closed or sealed by melting the glass. Before drawing out the end 18 the space 19 is charged with the serum or fluid in such a manner as to be entirely free from the contact of air and an inner rubber plug 16 is forced into nozzle 17. A small portion of mobile viscid substance, as for example glycerin is placed in nozzle 17 the nozzle being held so that the glycerin rests upon plug 20, a second plug 21, preferably of soft rubber, having a lesser curve on its inner end than the outer curve of the inner plug 20 so as to provide a small space 22 or break in the continuity of the completed soft rubber plug 21 and 22, which space is completely filled by the viscid substance as above described. The outer surface of the two plugs 20 and 21 are covered with cement before being insert-

ed in the nozzle 17 so that they are cemented firmly in place within the nozzle. A thin funnel-shaped glass or metallic guide 23 is cemented to the walls of the outer plug 21 5 which is formed in a funnel-shape to correspond to the funnel-shaped guide 23 so that when pressed against the plug 23 it adheres thereto. The nozzle 17 is then drawn out in the portion 18 and sealed, thereby 10 hermetically sealing the contained fluid.

Before the insertion of the charge of fluid or serum to be injected, the space 24 in the rear end of tube 10 is filled with volatile fluid like ethyl chlorid which on evaporating 15 exerts considerable pressure. The pressure of the fluid or condensed air, or other gas which may be introduced in space 24 should be sufficiently greater than the pressure of the fluid in space 19 so that when opportunity is given 20 for the fluid charge, another space 19 is to be ejected or injected the pressure of the fluid or condensed gas within space 24 will automatically discharge the same, pressing the elastic sack 14 into the opposite end, as shown in 25 dotted line in Figs. 1 and 2, the sack or collapsible partition 14 being shown in different degrees as it is advanced by the pressure thereof and is eventually turned inside out, thus completely expelling the contained 30 fluid.

Instead of the air or other fluid under pressure in space 24 to expel the charge in space 19 the end 11 of tube 10 is left open in a small glass bulb 25 having an orifice 26 there- 35 in and an elastic bulb 27 is provided of sufficient magnitude to produce the desired pressure upon sack 14 by the compression of bulb 27. Further modification is shown in Figs. 3 and 4, the piston 28 is inserted within tube 40 10 through orifice 26 in order to provide pressure upon sack 14 and the contained fluid.

On account of the danger of breakage of tube 10 due to the expansion and contraction of the contained fluid on account of the varying 45 temperature to which it may be subjected, it is necessary to provide a resilient holding or cushion for the contained fluid within space 19. Air has been used as such a cushion but since the purpose of this invention is 50 to entirely do away with the contact of air with the serum or other fluid to be injected, the resilient sack 14 is provided. In the case of a piston syringe such a resilient cushioning of the air tight receptacle might be at- 55 tained by the attachment of an air tight collapsible sack 29 on the face of the piston head 30, the sack 29 being filled with air and extending out into the space 19 within tube 10. It is apparent that such an arrangement 60 would form an air tight cushion for the contained fluid substance which would not allow the contact of the air upon the same.

In order to discharge the contained fluid from the syringe the nozzle 17 is broken off 65 at line X X as shown, and a hollow injecting

needle 31 is provided with a resistant stop 32 to prevent too great introduction of the needle into the nozzle. Stop 32 may be of any convenient form or material but is preferably a flat metallic plate soldered to the needle 31. 70 The needle 31 is pointed at ends 33 and 34, and end 33 extends through stop 32 to a sufficient distance to penetrate through the soft rubber plugs 20 and 21.

The outer end 34 of needle 31 is first inserted in the flesh where it is desired to inject the contained fluid, the inner end 33 is then inserted through the plugs 20 and 21, being guided thereto by the glass or metallic funnel 23 so as to quickly pierce the same and enter 80 the space 19 where the fluid is contained under pressure. It is apparent that injection may thus be made instantaneously without danger of injecting air and under perfectly antiseptic and germ-free conditions. 85 The space 19 may be charged or recharged by means of a hollow needle similar to 31, the inner point 33 being inserted through the soft rubber plugs 20 and 21. It is apparent that the fluid may be injected into the space 19 90 under as great a pressure as desired. The texture of the soft rubber plugs 20 and 21 with the viscous fluid therebetween being such that upon the withdrawal of needle 31, the needle puncture in this elastic material will 95 close, thus becoming self-healing and preventing the escape of the contained fluid. The funnel 23, the sides acting as a guide, is also used to support the soft rubber or elastic material used for plugs 20 and 21 so that this 100 self-healing principle may be intensified. After the injection of the fluid the outer end of the nozzle may be drawn out and resealed in a suitable flame. It is also apparent that such a syringe or receptacle may be cheaply 105 constructed and thus provide a receptacle for storing anti-toxic serum without contact of air hermetically sealed for an indefinite length of time. For this purpose it is obvious that the form shown in Fig. 1 is preferred 110 though either of the modifications might serve a good purpose.

I claim as new:

1. A receptacle for fluid under pressure consisting of an air tight receptacle, and a resilient air tight sack within said receptacle containing air under pressure to eject the fluid from said air-tight receptacle.

2. A receptacle for fluid under pressure consisting of an air-tight receptacle, a resilient air-tight sack within said receptacle containing air under pressure, and means for liberating the fluid from said air-tight receptacle.

3. A receptacle for fluid under pressure consisting of an air tight receptacle having a frangible end, a resilient collapsible air tight partition in said receptacle, substantially as and for the purpose specified.

4. A receptacle for fluid under pressure

consisting of a closed glass tube, a resilient collapsible air-tight sack in said tube, and means for injecting fluid into said tube, without contact of air.

5. A syringe consisting of a tube having an air tight space therein to contain fluid, a resilient partition in said tube forming one end of said air tight space, and means for producing pressure upon said resilient partition to 10 eject said fluid.

6. A syringe consisting of a tube having an air-tight space therein to contain fluid under pressure, two soft rubber plugs in one end of said tube, and a viscid fluid between said 15 plugs.

7. A syringe consisting of a tube having an air-tight space therein to contain fluid under pressure, two soft rubber plugs in one end of said tube, a viscid fluid between said plugs, and a funnel-shaped guide attached to the 20 outer plug, substantially as and for the purpose specified.

8. A syringe consisting of a glass tube hav-

ing an air tight space therein to contain fluid under pressure, a hermetically sealed nozzle on said tube to be broken off, two plugs of soft rubber in said nozzle, a viscid fluid between said plugs, and a suitable injecting needle for inserting through said plugs to discharge said fluid under pressure. 30

9. A syringe consisting of a tube 10 having hermetically sealed nozzle portion 17 thereon, a resilient air-tight partition 14 attached to the inner side of said tube, soft rubber plugs 20 and 21 in said nozzle having 35 space between them, and injecting needle 31 insertible through said plugs, and means for producing pressure on said resilient partition to eject said fluid through said needle.

In testimony whereof I have signed my 40 name to this specification in the presence of two subscribing witnesses.

BENJAMIN F. LOCKWOOD.
